UNITED STATES PATENT OFFICE

2,238,395

PUMP

Alfred Nittka, Elkton, Mich.

Application February 13, 1939, Serial No. 256,131

2 Claims.

(Cl. 103—5)

My invention relates to pumps, and its principal object is to provide means for producing an artificial pressure upon the surface of the water or other fluid in the well under conditions in which natural pressure upon the surface of the liquid is non-existent or is exhausted, and in order to enable those skilled in the art to which my invention relates to make and use my said invention, I will now describe a preferred embodiment of the same as applied to a rotary pump of the type described in my prior patent, Serial No. 2,065,090, issued December 22, 1936, reference being had to the accompanying drawing, in which—

Figure 1 shows an elevation partly in section of a complete pumping and storage equipment having my invention applied thereto.

Figure 2 is a vertical elevation of the pump, drawn to enlarged scale, taken in section on the center line.

Figure 3 is a horizontal sectional view taken on line 3—3 of Figure 2.

Figure 4 is a fragmentary section taken on line 4—4 of Figure 3 illustrating in general the construction of the air inlet and discharge valves, and

Figure 5 is a central vertical section showing the construction of a relief or blow-off valve which forms part of the storage tank to be hereinafter described.

Like characters designate corresponding parts throughout the several views.

Referring more particularly to Figure 1 of the drawing, P designates the pump provided with the central shaft 18 and driven through the pulley 28 and belt B from the pulley 28' upon the motor A which, in the present case, is electrically driven. 1 designates the inlet or suction pipe of the pump and 8 designates the outlet nozzle of the same, the said nozzle being connected through rubber or other flexible coupling 81 and pipe 82 to the lower portion of the storage tank T, the tank T being provided with an outlet pipe T' and with a float F adapted to rest upon the upper surface of the water in the tank and to operate at the required time through lever F' and switch S so as to cut off current to the motor A when the level in the tank reaches a predetermined point, the switch S being connected through wires W to the leads of the motor in the manner well known in the art.

The pump P follows in general the construction shown in the drawing of my prior patent before mentioned, comprising the outer casing 1 having the shaft 18 rotatably mounted in bearings 19, 20

and having an extension 18' upon which the pulley 28' is mounted. Upon the shaft 18 is the rotor 30 and in cooperative relation with the said rotor is a flap valve 13 hinged at 12, which controls the passage of liquid from the interior of the casing 1 to the outlet or discharge nozzle 8. Connected to or integral with the flap valve 13 is a lever 132, the said lever being connected by a link 133 to a piston 134. The piston 134 is slidably mounted in the cylinder 135 and the said cylinder is provided with inlet and outlet valves V', V2, respectively.

The valve V' is open to atmospheric pressure, while the valve V2 discharges into a pipe 9. The inlet pipe 7 is provided with a strainer or nozzle 77 positioned below the level of the water in the well W and provided with openings 78 as shown in Figure 1. The pipe 9 extends downwardly below the water level in the well, and is provided with a U-shaped portion 91 which is connected by a union U with a short pipe 92, the upper end of which, of bell mouth shape, is located within the nozzle or strainer 77.

Thus it will be seen that with each oscillatory movement of the flap valve 13, a corresponding vertical movement is imparted to the piston 134 and, as a result, an air pressure is set up within the well so that the amount of liquid raised at each rotation of the rotor 30 is very much increased.

In the present drawing, numerous component parts of the pump are designated by the same characters as are used in the prior patent above cited, so that no repetition of the same is deemed necessary. The valves V, V', together with their respective inlet and discharge chambers, are of such common construction to need no description.

It will be observed from the foregoing specification and by reference to the drawing that I have provided a mechanism which is well adapted to the purpose set forth, and while I have herein described and shown a preferred embodiment of my invention, it will be readily understood that various modifications in detail may be made to suit any particular or peculiar requirements without departing from the spirit of my invention as defined in the appended claims.

The blow off valve designated Z in Figure 1 and shown in detail in Figure 5 consists merely of a pipe Z' threaded secured at Z2 within the top of the tank T and having a piston Z5 normally pressed downwards by a spring Z4. The spring Z4 is adjusted by means of the screw cap Z3 so as to control the pressure upon the piston Z5 in

the proper manner, so that when a predetermined air pressure is reached within the tank the piston is raised so as to uncover the lateral port Z6, as will be understood.

Having thus described my said invention, what I claim and desire to secure by Letters Patent of the United States is:

1. The combination, with a pump having a housing, a rotor within said housing, a vertical suction pipe adapted to extend into a well, an outlet opening, and an oscillatory valve member operated in one direction by said rotor and having resilient means for operating it in the other direction so as to control the flow of liquid from said housing to said outlet opening; of an air pump having a cylinder, a piston in said cylinder, link means connecting said piston with said valve member, and a discharge pipe upon said air pump terminating within the lower end of said suction pipe, whereby air is delivered to said suction pipe upon each oscillation of said valve member.

2. The combination, with a pump having a housing, a rotor within said housing, a vertical suction pipe adapted to extend into a well, an outlet opening, and an oscillatory valve member operated in one direction by said rotor and having resilient means for operating it in the other direction so as to control the flow of liquid from said housing to said outlet opening; of a cylinder adjacent said outlet opening, a piston in said cylinder, an air inlet valve open to the atmosphere, a discharge pipe having an upwardly turned portion terminating within the lower end of said suction pipe, a lever carried upon said valve member, and link means connecting said piston to said lever, whereby air is delivered to said suction pipe upon each oscillation of said valve member.

ALFRED NITTKA.
